UNITED STATES PATENT OFFICE

102,788

DESIGN FOR A GAME DEVICE

Richard W. Hood, Chicago, Ill., assignor to H. C. Evans & Company, Chicago, Ill., a corporation of Illinois

Application October 29, 1936, Serial No 65,575

Term of patent 7 years

To all whom it may concern:

Be it known that I, Richard W. Hood, a citizen of the United States, residing at Chicago, in the county of Cook and State of Illinois, have invented a new, original, and ornamental Design for Game Devices, of which the following is a specification, reference being had to the accompanying drawings, forming a part thereof.

In the drawings:

Fig. I is a front elevational view of the game device, showing my new design;

Fig. II is an end view thereof;
Fig. III is a top view thereof.

The numerals appearing on Figures I and III vary in the operation and use of the device and are shown merely for the purpose of illustration.

I claim:

The ornamental design for a game device, as shown and described.

RICHARD W. HOOD.
